COMBINED THERMOMETER CASE AND TIMER

Robert L. Huntsman, Broomall, Pa.

Application October 9, 1953, Serial No. 27,124

Term of patent 14 years

(Cl. D52—7)

To all whom it may concern:

Be it known that I, Robert L. Huntsman, a citizen of the United States, residing at Broomall, in the county of Delaware and State of Pennsylvania, have invented a new, original, and ornamental Design for a Combined Thermometer Case and Timer, of which the following is a specification, reference being had to the accompanying drawing, forming a part hereof.

Figure 1 is a side elevational view of a combined thermometer case and timer showing my new design;

Figure 2 is a perspective view thereof; and

Figure 3 is a partial perspective view of the top portion of the combined thermometer case and timer with the cap pivoted to its open position.

I claim:

The ornamental design for a combined thermometer case and timer, as shown.
